AIR AND WATER CONTROL MECHANISM

August H. Katterjohn, Detroit, Mich., assignor to
 Chicago Pneumatic Tool Company, New York,
 N. Y., a corporation of New Jersey

Application July 6, 1940, Serial No. 344,224

5 Claims. (CL. 277—3)

This invention relates generally to the operating controls of a percussive tool and more particularly to an improved combination air and water throttle control mechanism for use in rock drills and like tools.

The practice of spotting or starting a drill hole without first splashing the surface of the rock with water is largely responsible for the excessive dust conditions frequently found in mines and other confined working areas. So long as rock drills are constructed with independent throttle valves for the air and water connections, it is possible for operators to follow this practice of "dry spotting" and they frequently do so in preference to the time consuming routine of operating separate valves in a set sequence. Some effort has been made to place the air valve and water valve under the control of a single operating lever and the prior art gives a few instances of combined controls in which the separate valves can only be opened in the desired sequence. All such constructions necessitate an operating connection between the valves and this fact has presented a new problem in that an exchange of air and water, by seepage between the respective fluid inlets, is permitted. The entrance of water into the passages of the compressed air distributing system may cause corrosion and seriously interfere with moving parts within the tool and a construction permitting such an occurrence is therefore undesirable.

This invention presents a combined air and water throttle control mechanism that improves upon prior art structures through the provision of a bellows which acts as a positive seal between the air and water inlets and performs the additional function of transmitting motion from the air valve to the water valve.

One object of the invention is to eliminate the possibility of air and water seepage along an operating connection intermediate air and water valves.

Another object of the invention is to seal air and water inlets from each other by a fluid tight means including a bellows.

A further object of the invention is to seal air and water inlets from each other by a fluid tight means capable of transmitting motion.

Other objects and structural details of the invention will be more apparent from the following description when read in conjunction with the accompanying drawings, wherein:

Fig. 1 is a longitudinal section of the rear portion of a rock drill embodying the mechanism

of the invention, taken through the broken line 1—1 in Fig. 2;

Fig. 2 is a rear end view of the tool shown in Fig. 1;

Fig. 3 is a fragmentary view taken along the line 3—3 of Fig. 2 showing the air throttle valve in open position;

Fig. 4 is a view in cross-section of the water valve assembly and is taken along the line 4—4 of Fig. 1; and

Fig. 5 is a detail view, partly in section, of the bellows.

The air and water throttle control is illustrated in Fig. 1 in operative relation to a distributing valve and water tube of conventional types. The illustrative drill includes a backhead 10 in which the throttle control mechanism is mounted, a barrel 11, secured to the backhead 10, and having a piston chamber 12 formed therein, and a hammer piston 13 reciprocable within the chamber 12 to deliver blows of percussion to a working implement (not shown) mounted at the front end of the drill. The piston 13 is slidably mounted on a rifle bar 14 which is caused, by means including a ratchet ring 15, to move in a step-by-step rotary movement, which movement is imparted to the piston 13 through a nut 16 fixed within the piston and engaging the helical splines formed on the rifle bar. The reciprocating movement of the piston 13 is effected by compressed air admitted to the tool under the control of an air throttle valve 17 and directed by a distributing valve assembly 18 to alternate ends of the chamber 12. The valve assembly 18, comprising generally a casing 19, a bushing 21 and reciprocable cylindrical valve 22, is positioned within the barrel 11 and encircles the shank of the rifle bar 14.

Referring also to Figs. 2 and 3, it will be seen that the air throttle valve 17 is generally tubular in shape and is positioned in a bore 23 extending transversely through the upper front end of the backhead 10. A compressed air conducting hose line 24 (Fig. 2) extends into one end of the bore 23 and air flowing into the bore passes into a chamber 25 (Figs. 1 and 3) formed within the valve 17 throughout a portion of its length. The left hand end of the valve 17, as viewed in Fig. 2, is reduced to form an extension 17a which projects outside the bore 23 and has secured thereto a manually operable lever 26 by which the valve may be oscillated to place a port 27 (Fig. 3) therein, into and out of registry with an air passage 28. With the valve 17 positioned as shown in Fig. 3 air flowing into the chamber

25 is permitted to pass out the port 27 to passage 23 and is then conducted around an annular groove 29 and through a port 31, in ratchet ring 15, to the ports and passages of the distributing valve assembly 18. Upon movement of the throttle valve 17 to the position shown in Fig. 1 the port 27 is placed out of registry with the passage 28 to prevent the flow of air from chamber 25 and thereby stop operation of the drill.

As shown in Fig. 1, the means for conducting water through the tool for use as a cleansing fluid comprises a centrally positioned water tube 32 leading from the backhead 10 through the rifle bar 14 and hammer piston 13 to the front end of the toll. Water, under moderate pressure, is directed through the tube 32 and forced through a longitudinal passage in the drill steel to wash out the cut material, or detritus, from the drill hole and allay dust. The rear end of the tube 32 extends into a bore 33 in the backhead 10 to which water is directed through a passage 34. The bore 33 is closed by a plug 35 which, in cooperation with a spacing ring 36 and resilient cushion 37, encloses the adjacent end of the water tube. The spacing ring 36 and cushion 37 are positioned between a flange 38 on the tube 32 and the inner end of the bore 33, while the inner end of the plug 35 engages the spacing ring 36 and is formed with a recess 39 receiving the flange 38. The inner end of plug 35 is reduced to permit the flow of water from the passage 34 into the bore 33, and communication is established between the area surrounding the reduced portion of the plug 35 and recess 39 by a set of transverse ports 41 and a longitudinal passage 42, in the plug.

Considering now the water inlet and means for controlling the flow of water to the passage 34 and bore 33, the water enters the drill through a bore 43, in backhead 10, to which it is conducted by a hose line 44 (Fig. 2). From bore 43, the water passes through a passage 45 to another bore 46 with which the passage 34 also communicates. The bore 46 is closed by a cap 47 and positioned within the bore is a bushing 48 having an annular groove 49 registering with the passage 45. A set of ports 51 connect the groove 49 to a recess 52 in the outer end of the bushing 48, and a central passage 53 connects the recess 52 to an oppositely disposed recess 54 in the inner end of the bushing. The inner recess 54 communicates with the passage 34 through a set of ports 55 and an annular groove 56 formed in the bore 46. The flow of water from bore 43 to the recess, or inlet chamber, 52 is unrestricted but a valve 57 movable to open and closed positions with respect to the central passage 53 controls the flow from outer recess 52 to inner recess 54. A spring 58, interposed between the cap 47 and valve 57 presses the valve to the position illustrated, in which communication between the recesses 52 and 54 is cut off and the passage of water to the tube 32 is prevented. In order that the valve 57 may be moved off its seat in the outer end of passage 53 to open position it is provided with a stem 59 extending through the passage 53 into the recess 54, in alignment with an actuating plunger 61.

The plunger 61 is movable within a bushing 62 supported at the inner end of the bore 46 and extending partly within a passage 63 connecting bore 46 and the air inlet bore 23. The inner end of the plunger 61 projects into the bore 23 in cooperative relation with a flange 64 formed on the right hand end (Fig. 2) of the throttle

valve 17. The flange 64 occupies only a portion of the circumference of the valve 17 and its opposite ends are formed as inclined cam surfaces 65 (Fig. 1). One of the cam surfaces 65 is positioned adjacent the plunger and is adapted, upon rotation of the throttle valve, to engage the plunger and move it leftward to unseat valve 57. As shown in Fig. 1, in the normal, or closed, position of the throttle valve 17, the cam surface 65 adjacent the plunger 61 is located immediately above the inner end of the plunger. Thus, at the very start of the counterclockwise movement of the throttle valve to open position the plunger 61 is cammed outward and the valve 57 is opened to admit water to the tube 32 before port 27 is brought to registry with the passage 28 to initiate operation of the hammer piston. When the throttle valve 17 is restored to closed position the spring 58 is permitted to return the valve 57 and plunger 61 to the normal position of Fig. 1. In order that the valve 57 may be guided within the passage 53, the stem 59 of the valve is formed with a plurality of ribs 59a (see also Fig. 4) engageable with the wall of the passage and spaced apart to permit the free flow of water from recess 52 to recess 54.

The mechanism described above, whereby the air throttle valve and the water valve are placed under the control of a common operating means, simplifies operation of the tool and presents another advantage in that it makes it impossible for the operator to begin drilling without first spraying the work with a stream of water. Such a construction presents a problem, however, since, with the tool in constant use, water from the recess 54 tends to seep along the plunger 61 into the bore 23 and to be blown into the air passages of the valve assembly 18. This difficulty, present in prior art structures of this class, is overcome by the present invention through the provision of a metallic bellows 66 (see also Fig. 5) which encloses the portion of bushing 62 and that end of the plunger 61 which extend into the recess 54. The base 67 of bellows 66 flares outward and is secured between the inner end of the bushing 48 and a flange 68 formed on the bushing 62. The outer end of the bellows is closed by a disc 69 pressed into a fluid tight engagement with the end surface of the bellows. The valve stem 59 and plunger 61 engage the disc 69 on opposite sides thereof and effect movement of each other through compression and expansion of the bellows relatively to its fixed base 67. The manner in which the base 67 of the bellows is clamped between the bushings 48 and 62 renders this connection fluid tight. Air, seeping into the bellows 66 along the plunger 61, may find its way to the atmosphere through a port 71 and groove 72, in bushing 62, opening into an exhaust passage 73.

Although the bellows 66 is preferably constructed of metal, other materials may be used in its construction without departure from the present invention.

65 What is claimed is:

1. In a device of the class described, the combination of a main air inlet, a first valve settable to closed and open positions to prevent and permit the flow of air from said main air inlet, a water inlet to which water under pressure is directed for use as a cleansing fluid, a second valve settable to closed and open positions to prevent and permit the flow of water from said water inlet, a plunger controlled by movement of said first valve and extending from said air inlet

into cooperative relation with said second valve, and a bellows transmitting the movement of said plunger to said second valve and acting as a seal between the air and water inlets.

2. In a device of the class described, the combination of a main air inlet, a first valve settable to closed and open positions to prevent and permit the flow of air from said main air inlet, a water inlet to which water under pressure is directed for use as a cleansing fluid, a second valve settable to closed and open positions to prevent and permit the flow of water from said water inlet, a plunger controlled by movement of said first valve and extending from said air inlet into cooperative relation with said second valve, and a bellows positioned between said plunger and said second valve to cut off communication between said water inlet and said air inlet and engaged on one side by said plunger and on the other side by said second valve to transmit the movement of each of said elements to the other.

3. In a device of the class described, the combination of a main air inlet, a first valve settable to closed and open positions to prevent and permit the flow of air from said main air inlet, a water inlet to which water under pressure is directed for use as a cleansing fluid, a second valve settable to closed and open positions to prevent and permit the flow of water from said water inlet, a plunger extending between said air inlet and said water inlet and disposed with its opposite ends in cooperative relation respectively with said first valve and said second valve, a cam surface on said first valve arranged to actuate said plunger upon movement of said first valve toward open position, and a bellows enclosing one end of said plunger to prevent the passage of water and air to and from said main air inlet around said plunger, said bellows acting in cooperation with said plunger to transmit the movement of said first valve to said second valve.

4. In a device of the class described, the combination of a main air inlet, a first valve settable to closed and open positions to prevent and permit the flow of air from said main air inlet, a water inlet to which water under pressure is

directed for use as a cleansing fluid, a passageway leading from said water inlet through which water is directed from said water inlet, a second valve positioned in said passageway and settable to closed and open positions to prevent and permit the flow of water through said passageway, a valve actuating plunger having one end extending into said passageway adjacent said second valve and having its opposite end extending into said main air inlet adjacent said first valve, a cam surface on said first valve arranged to actuate said plunger upon movement of said first valve toward open position, and a bellows enclosing that end of said plunger which extends into said passageway to prevent the passage of water and air to and from said main air inlet around said plunger, said bellows acting in cooperation with said plunger to transmit the movement of said first valve to said second valve.

5. In a device of the class described having separate air and water inlets, the combination of a throttle valve within said air inlet and movable to closed and open positions to prevent and permit the flow of air therefrom, a bushing positioned in said water inlet and having a rearwardly facing recess and a forwardly facing recess, a central passage in said bushing connecting said rearwardly and forwardly facing recesses, a control valve movable to closed and open positions with respect to said central passage to prevent and permit the passage of water from one to another of said recesses, a valve actuating plunger having one end extending into one of said recesses adjacent said control valve and having its opposite end extending into said air inlet adjacent said throttle valve, a cam surface on said throttle valve arranged to actuate said plunger upon movement of said throttle valve toward open position, and a bellows enclosing that end of said plunger which is adjacent said control valve to prevent the passage of water and air to and from said air inlet around said plunger, said bellows acting in cooperation with said plunger to transmit the movement of said throttle valve to said control valve.

AUGUST H. KATTERJOHN.
